DESIGN FOR A COVER FOR A CHAIR SEAT CUSHION

Aaron Traum, New York, N. Y.

Application October 15, 1941, Serial No. 103,771

Term of patent 14 years

To all whom it may concern:

Be it known that I, Aaron Traum, a citizen of the United States of America, residing in New York city, county of New York, and State of New York, have invented a new, original, and ornamental Design for a Cover for a Chair Seat Cushion, of which the following is a specification, reference being had to the accompanying drawing, forming part thereof, wherein,

I claim:

The ornamental design for a cover for a chair seat cushion, substantially as shown.

AARON TRAUM.
